(57) **CLAIM**

The ornamental design for a temporary tattoo cover, as
shown and described.

DESCRIPTION

This application contains subject matter similar to that
disclosed in U.S. application Ser. No. 11/121,253, which
was filed May 3, 2005, and is hereby incorporated by
reference in its entirety.

FIG. 1 is a top plan view of a temporary tattoo cover,
illustrating an opaque layer and a contrasting transparent or
translucent layer underneath the opaque layer, wherein one-
half of the opaque layer is removed;

FIG. 2 is a left side elevational view of the temporary tattoo
cover of FIG. 1, the right side elevational view is a mirror
image of FIG. 2;

FIG. 3 is a front elevational view of the temporary tattoo
cover of FIG. 1, the back elevational view is identical to
FIG. 3;

FIG. 4 is a top plan view of an alternative embodiment of a
temporary tattoo cover;

FIG. 5 is left side elevational view of the temporary tattoo
cover of FIG. 4, the right side elevational view is identical to
FIG. 5;

FIG. 6 is a front elevational view of the temporary tattoo
cover of FIG. 4, the back elevational view is identical to
FIG. 6; and,

FIG. 7 is a bottom plan view of the temporary tattoo cover
of FIG. 4.

The broken lines in the figures show structure or boundaries
that are not part of the claimed design, but rather show the
environment in which the design is associated, or show
portions of the article in which the design is embodied or
applied to that are not considered part of the claimed design.
The vertical shading lines indicate opaque surfaces, and the
oblique shading lines indicate contrasting transparent or
translucent surfaces.
